GRINDING WHEEL AND MEANS FOR MOUNTING THE SAME

Filed Jan. 28, 1928

Inventor
Thaddeus A. Jackson
By his Attorney
A. R. Appleman

UNITED STATES PATENT OFFICE

THADDEUS A. JACKSON, OF BROOKLYN, NEW YORK, ASSIGNOR OF ONE-HALF TO WILLIAM J. SKELLY, OF NEW YORK, N. Y.

GRINDING WHEEL AND MEANS FOR MOUNTING THE SAME

Application filed January 28, 1928. Serial No. 250,243.

This invention relates to grinding wheels and means for mounting the same. The object being to provide a grinding wheel for general purposes and a mount therefor whereby work can be passed entirely across the outer face of said wheel when in operation. Said mount having means whereby the wheel may be accurately centered thereon and quickly removed when desired.

10 Features of the invention are present first, in providing the grinding wheel with side depressions having flaring or beveled side walls, the depressions in the outer face or side of the wheel being preferably of a depth greater than that in the opposite face.

Further features of the invention are found in an arbor having a conical shoulder and an extended circular flange and cheek pieces, plates or disks having flared peripheral edges and inwardly converging central portions providing conical sockets or chambers terminating in short sleeves bearing on said arbor.

The outer end of the arbor terminates within the plane of the outer face of the wheel and is provided with short spiral grooves on which a nut, having a conical inner face and a circular flange, is threaded, said nut having wings or projections by which it may be loosened and turned off the arbor when the wheel is to be removed.

The invention possesses other advantageous features, which, with the foregoing will be set forth in the following description and it will be understood that I do not limit myself to the construction shown as I may adopt many variations within the scope of the invention claimed.

In the drawings forming part of this specification similar characters of reference are employed to designate corresponding parts throughout the several views, in which:

Fig. 1 is a central vertical sectional elevation of my improved emery wheel and the means for mounting the same, the locking nut being indicated as removed in dotted lines,

Fig. 2 is an outside face view of the device,

Fig. 3 is a detail side elevation of a portion 50 of the arbor.

Referring to the drawings in detail, 10 indicates the improved grinding wheel made of emery or other material, having a central bore 11, and recesses or depressions 12 and 13, formed in the opposite sides thereof and it is 55 preferably reinforced against high speed centrifugal strains by a disk or sheet of heavy wire mesh 14 moulded into the wheel structure as shown.

In carrying out my invention, I provide an arbor 15, formed with an integral circumferential shoulder 16, formed with an extended flange 17 and a conical face portion 18.

To properly center or balance the grinder wheel 10 on its arbor 15, I provide companion cheek disks, plates or pieces 19, which may be stamped or formed with flared peripheral edges 20 to fit snugly within the flared walls 21 of the depressions or recesses 12 and 13 at the opposite sides of the wheel, as shown in Fig. 1 of the drawings.

The disks 19, are pressed inwardly at their centers producing inwardly converging or flaring portions 22, terminating in short sleeves 23, which bear on and enclose the arbor 15. The converging portions 22 of the disks 19 provide conical sockets or chambers 24 and 25, adapted to receive in intimate relation, the conical face portion 18, of the arbor and a cone or conical face portion 26 of a 80 nut 27.

The free or outer end of the arbor 15, is preferably provided with spiral grooves or channels 28, to receive corresponding spiral threads or ribs 29 in the bore of the nut as 85 shown in Fig. 2 of the drawings.

To facilitate the removal of the nut by backing up on the threads, I provide it with wings, lugs or projections 30, against which a hammer or other tool may be tapped lightly 90 to start the backward movement.

It will be noted that the spiral grooves extend less than a third around the arbor and the threads of the nut the same, so that the nut is quickly bottomed and removed, the direction of spiral of the grooves being in the direction of rotation of the wheel, so that the nut is constantly jammed down into clamping relation with the parts.

The nut 27 has also formed therewith a cir- 100

cumferential flange 31, corresponding to the flange 17 on the arbor shoulder 16, which flanges normally bear against the plates 19 outwardly of the conical chambers 24 and 25 when the parts are assembled. Adjustments can be made by placing shim rings or pieces back of the said flanges as will be understood.

Having thus described my invention, what I claim and desire to secure by Letters Patent is:

- 10 1. A grinding wheel having a central bore and recesses at its opposite sides, the recesses having flat parallel bottoms and outwardly flaring straight circumferential walls, in combination with means for mounting said wheel, comprising companion cheek plates each having a straight peripheral flaring flange to intimately engage the flaring wall of its corresponding recess, a flat body portion, a 20 conical socket having a central opening and a unitary inwardly directed sleeve, the conical socket and sleeve of each cheek plate extending within the wheel bore at both ends thereof, an arbor having a conical shoulder to 25 engage the socket of one cheek plate and a nut having a conical shoulder to engage the socket of the opposite cheek plate for clamping the said plates to center and support said wheel.
- 30 2. A grinding wheel having a central bore and opposite circular depressions provided with outwardly flaring straight circumferential walls, in combination with cheek plates shaped to intimately engage said walls and 35 having conical sockets with central openings and unitary sleeves projecting inwardly from either end of said bore, an arbor and a clamping nut, each having a conical portion to fit said sockets and an extended circumferential 40 flange bearing against the bottom of the recesses at the edge of said bore as shown and described.

In testimony whereof, I have signed my name to this specification, this 27th day of January, 1928.

THADDEUS A. JACKSON.
